UNITED STATES PATENT OFFICE.

DANIEL W. TOWER, OF GRAND RAPIDS, MICHIGAN, ASSIGNOR TO GRAND RAPIDS
BRASS COMPANY, OF GRAND RAPIDS, MICHIGAN.

LATCH.

980,458.

Specification of Letters Patent.

Patented Jan. 3, 1911.

Application filed April 3, 1909. Serial No. 487,698.

To all whom it may concern:

Be it known that I, DANIEL W. TOWER, a citizen of the United States, residing at Grand Rapids, Michigan, have invented certain new and useful Improvements in Latches, of which the following is a specification.

This invention relates to improvements in latches.

10 The main objects of this invention are: First, to provide an improved latch which is adapted for use on a right or left hand opening door without the necessity for making any changes in the latch, it only being necessary to reverse its position. Second, 15 to provide an improved latch which is very simple and economical in structure.

Further objects, and objects relating to structural details, will definitely appear 20 from the detailed description to follow.

I accomplish the objects of my invention by the devices and means described in the following specification.

The invention is clearly defined and pointed out in the claims.

A structure embodying the features of my invention is clearly illustrated in the accompanying drawing, forming a part of this specification, in which:

30 Figure 1 is a detail front elevation of a structure embodying the features of my invention. Fig. 2 is a detail section taken on a line corresponding to line 2—2 of Fig. 1. Fig. 3 is an inverted plan view of the structure appearing in Figs. 1 and 2 removed from the door. Fig. 4 is a vertical section taken on a line corresponding to line 4—4 of Fig. 1. Fig. 5 is a detail inverted plan of a modified construction, a single spring 35 being employed instead of the double springs shown in Figs. 1 to 4. Fig. 6 is a plan of a further modification of the latch, it being a non-reversible structure, the modification being merely in the arrangement of the spring.

40 Fig. 7 is an inverted plan of a further modification showing a reversible structure with springs arranged as in Fig. 6. Fig. 8 is an inverted plan of a further modification, it being a non-reversible structure, the modification being in the arrangement and attachment of the spring, a compression spring 45 being here used, whereas in the structures before described, extension springs are illustrated. Fig. 9 is an inverted plan view of a

50 still further modification in the matter of the 55 arrangement of the springs, the structure illustrated being the same as that of Fig. 8, except that it is a reversible structure. Fig. 10 is an inverted plan of a further modification in the arrangement of the springs. Fig. 60 60 Fig. 11 is a detail section showing the manner of striking the lugs 21 up from the latch plate flange.

65 In the drawings, similar reference characters refer to similar parts throughout the several views, and the sectional views are taken looking in the direction of the little arrows at the ends of the section lines.

70 Referring to the drawing, 1 represents a door and 2 a door casing, the latch being 70 shown in Figs. 1 and 2 in its operative relation. The latch plate 3 is provided with an inwardly-projecting flange 4 at its edges. The latch plate and its flange are preferably 75 formed up of an integral sheet metal stamping and constitute the casing of the latch. On one side the flange is provided with a slot 5, the inner edge of the slot being located in substantially the same plane as the inner edge of the latch plate. The latch bolt 6 80 is arranged through the slot so that the edges of the slot serve to support the latch bolt and the ends of the slot serve as stops therefor.

85 The latch plate is provided with suitable holes 8 to receive the screws 9, by which it is attached. The latch bolt 6 is secured to the inner end of the knob or finger piece, as clearly appears from the drawing, the knob 90 being journaled in the latch plate, thus serving as a pivot for the bolt. The finger piece or knob is preferably made up of sheet metal and comprises a cylindrical barrel portion 10 flared outwardly at its outer end 11, on which the end-piece 12 is secured by turning 95 or seaming the edges of the end portion 12 over the edges of the flange 11, as clearly appears from Fig. 4. This forms a neat finish for the knob and is very convenient to grasp.

100 The barrel portion of the knob is shouldered at 13 to form a bearing 14 which is arranged in the bearing opening 15 in the latch plate. The portion of the barrel below the latch plate is reduced to form a stud 16 which is arranged through the opening 105 in the bolt and secured by the out-turned flange 17. This forms a very simple construction, which is, at the same time, entirely effective for the purpose and attractive in 110 appearance.

The springs 18, which are of the coiled type, are preferably secured at one end to the lugs 19 on the flanges which are perforated to receive the same, and at the other ends to the perforated lugs 20 on the latch bolt. These springs are preferably arranged in pairs in the structures which are designed to be reversible, so that the latch bolt is held centrally in position, as is illustrated in Figs. 3, 11, 13 and 14, a single spring, however, being arranged to accomplish the purpose in Fig. 5.

The structure illustrated in Figs. 6 and 8 is what I designate as non-reversible,— that is, the latch bolt can swing in but one direction from its normal position. By this arrangement of the parts, I secure a structure which is very simple and economical, and is, at the same time, very effective and compact and attractive in appearance.

In the modified structure shown in Fig. 5, a single spring is arranged to accomplish the function of two springs, it being so connected to the latch bolt relative to the pivot 25 of the bolt that it returns it to its central or normal position.

In the modified structure of Fig. 6, the spring is secured to the latch bolt in front of the bolt pivot. The modification of Fig. 30 7 has the same arrangement of springs applied to a reversible structure.

In the modification shown in Figs. 8 to 11, inclusive, compression springs are used instead of expansion springs, the spring-engaging lugs 21 on the casing flange and the lugs 22 on the latch bolt being adapted to receive the ends of the springs, as clearly appears from the drawing. The structure of Fig. 9 is substantially that of Fig. 8, modified to form a reversible latch. The modified structure of Fig. 10 is substantially that of Fig. 9, the position of the parts being reversed, the lugs on the bolt facing forwardly rather than rearwardly. These lugs are so arranged that they support the spring effectively.

I have illustrated these various modifications to show the general adaptability of my improvements. Other modifications will undoubtedly be suggested by these illustrations to those skilled in the art to which this invention relates.

Having thus described my invention, what I claim as new and desire to secure by Letters Patent is:

1. The combination with the casing comprising a latch plate having an inwardly-projecting flange at its edges, said flange having a slot therein at one side; a latch bolt arranged through said slot in said flange, the ends of which serve as stops therefor; a finger piece and handle to which said latch bolt is secured, pivotally mounted on said plate; a pair of inwardly-projecting 60 perforated spring-attaching lugs on said

flange;—a pair of oppositely-disposed perforated spring-attaching lugs on said latch bolt; and coiled springs engaged with said spring-attaching lugs on said flange and latch bolt whereby said bolt is held uniformly in a central position and is adapted to be swung in either direction from such position.

2. A latch comprising a plate having a marginal flange provided with a recess, a hollow stamped sheet metal knob having a hollow sheet metal member rotative in the plate and provided with a non-circular inner end clenched on the inner side of the bolt and a bolt projecting through the recess and movable therein and also having a non-circular opening to receive the non-circular end of the knob.

3. The combination with the casing comprising a latch plate having a bearing opening therein; a latch bolt; a finger piece and handle for said latch bolt comprising a cylindrical barrel portion formed of sheet metal, said barrel being shouldered at its lower end to form a bearing portion which is arranged in said bearing opening in said latch plate, the portion below said bearing portion being arranged through and clenched on the inner side of said bolt, a portion of said barrel arranged through said bolt being non-circular, said bolt having a non-circular opening to receive the same whereby said finger piece is secured to said bolt and pivotally supported in said latch plate.

4. The combination with the casing comprising a latch plate having an inwardly-projecting flange at its edges, said flange having a slot therein at one side; a latch bolt arranged through said slot in said flange, the ends of which serve as stops therefor to limit its outward swing in both directions; a finger piece to which said latch bolt is secured, pivotally mounted on said plate; and coiled springs secured to said flange and latch bolt, said springs being attached to said flange on opposite sides of its pivot whereby said latch bolt is held yieldingly in a central position in said slot.

5. The combination with the casing comprising a latch plate formed of sheet metal stamping and having inwardly-projecting spring-attaching lugs formed by turning inwardly portions of said flange; a latch bolt having opposed attaching lugs formed integrally therewith; and coiled springs engaged with said spring-attaching lugs on said flange and latch bolt whereby said bolt is held normally in a central position by said springs.

6. The combination with the casing comprising a latch plate formed of a sheet metal stamping having an inwardly-projecting flange at its edges, said flange having integrally formed spring-attaching lugs there-

on formed by punching inwardly portions thereof; a latch bolt formed of sheet metal stamping and having an integrally formed spring attaching lug thereon; and a coiled 5 spring engaged with said spring-attaching lugs on said flange and latch bolt.

In witness whereof, I have hereunto set

my hand and seal in the presence of two witnesses.
